(57) **CLAIM**

The ornamental design for a ribbon decoration device, as shown and described.

DESCRIPTION

FIG. 1 is a back view of a ribbon decoration device showing my new design in a closed and rolled configuration;

FIG. 2 is a front view of FIG. 1 with the ribbons shown in a partially unrolled configuration;

FIG. 3 is another front view of FIG. 1 with the ribbons shown in a fully unrolled configuration;

FIG. 4 is a front view of FIG. 1;

FIG. 5 is a front view of FIG. 2;

FIG. 6 is a front view of FIG. 3;

FIG. 7 is a bottom view of FIG. 1;

FIG. 8 is a top view of FIG. 1;

FIG. 9 is a right side view of FIG. 2;

FIG. 10 is a left side view of FIG. 2;

FIG. 11 is a top perspective view of FIG. 8, shown in a wrapped configuration; and,

FIG. 12 is a bottom perspective view of FIG. 11.

The even dashed broken lines illustrate button snaps and stitching and form no part of the claimed design.

The dot, dot dashed broken lines on the ribbon device show that the ribbon is broken away in FIGS. 1-10 to indicate that no particular length is claimed and that the appearance of any portion of the article between the break lines forms no part of the claimed design.
